UNITED STATES PATENT OFFICE.

FRANK B. PALMER, OF DORRANCETON BOROUGH, PENNSYLVANIA, ASSIGNOR TO WALES ADDING MACHINE COMPANY, OF WILKES-BARRE, PENNSYLVANIA, A CORPORATION OF PENNSYLVANIA.

CALCULATING-MACHINE.

1,330,278.

Specification of Letters Patent.

Patented Feb. 10, 1920.

Application filed May 17, 1919. Serial No. 297,801.

To all whom it may concern:

Be it known that I, FRANK B. PALMER, a citizen of the United States, residing in the borough of Dorranceton, Luzerne county, Pennsylvania, have invented new and useful Improvements in Calculating-Machines, of which the following is a specification.

More particularly, this invention relates to automatic non-print mechanism, designed 10 to prevent printing in one or more denominations, and permitting printing in the remaining denominations.

The invention is an improvement in the device shown in U. S. patent to Pentecost, 15 1,282,282, October 22, 1918, wherein a denominational typecarrier, if shifted to, or past a predetermined point, actuates means to prevent effective operation of the printing hammer associated with another denomination, to thereby eliminate printing of 20 ciphers (or other characters) in such last-named denomination.

In the patent, the desired result is obtained by locking the usual printing hammer 25 to render it inactive, such lock being directly actuated by the selected typecarrier.

Objects of this invention are the simplification and improvement of the former mechanism, and reduction in the number of parts 30 employed, together with a consequent reduction in the expense of manufacture and the labor of assembling and adjusting the device in a calculating machine, which ends, I attain by utilizing a different principle to arrive 35 at the same result.

Thus, I do not interfere with the activity of the usual printing hammers, but so arrange the mechanism that such activity is rendered ineffectual.

40 In so doing, I have provided a novel device which is readily applicable to machines already in use, and is not liable to get out of order or require repairs.

To these and other ends, my invention includes 45 the novel features and combinations of parts hereinafter more fully disclosed and particularly pointed out in the claims.

In the accompanying drawings, Figure 1 is a longitudinal sectional view through the 50 well-known Wales calculating machine, in connection with which I have chosen to illustrate my invention, the elements being in their normal positions of rest, and certain of

the usual parts which are unrelated to the present invention, being omitted;

55

Fig. 2 is a similar view, showing the positions of the parts at the end of the forward stroke of the main drive shaft;

Fig. 3 is a fragmentary plan view of the keyboard section, the drive members and 60 counters being shown in dotted lines;

Fig. 4 is a detail plan, showing a part of my invention; and

Fig. 5 is a perspective view of a rack 65 detent equipped with means to enable its control by the stops of another denomination.

Many of the principal features of the Wales machine are so completely disclosed in U. S. patents to Wales, 794,205, July 11, 1905, and 797,032, August 15, 1905; and McFarland & Wales, 880,157, February 25, 1908; that an extended explanation thereof is unnecessary.

Briefly, the machine includes a keyboard having a plurality of denominational rows 70 or banks of numeral keys 117, (Figs 1 and 2) each row comprising individual numeral keys from "1" to "9" respectively (in the decimal system. See Fig. 3.

75

The keys in each denominational row, individually control the respective stops 115 arranged in files corresponding with their respective rows of keys, to variously arrest the excursions of denominational positioning bars or drive racks 310.

80

Front arms 312 (Fig. 1) journaled on a cross shaft 300, and rear arms 311 journaled on a cross rod 301, pivotally support the several positioning bars or drive members 310 for forward and backward reciprocation. Drive springs 383 conveniently connected to the several rear arms 311 and to a restraining and restoring bar 205, tend to advance the positioning bars, such advance being normally prevented by the restraining and restoring bar which extends across the machine in front of the several front supporting arms 312 to hold the latter, with the racks 310, in their retired positions, see Fig. 1.

85

The restraining and restoring bar 205 is supported and operated as follows.

90

A rock shaft 265 extending across the machine, carries depending fingers 265^m in which the restraining and restoring bar 205 105 is mounted, and a crank 220 (Fig. 1) having

100

a cam slot 220^m is secured to the rock shaft 265. A wiper 256 projecting from an arm 210 fast on the main drive shaft 200, traverses the cam slot 220^m to oscillate the crank 220 and swing the restraining bar 205 from and toward the front supporting arms 312.

Normally, the wiper lies at one end of the cam slot 220^m to lock the crank 220 and the restraining and restoring bar 205 in their 10 home positions.

Counters 490, journaled for independent rotation on a counter axle 400 extending across the machine above the positioning racks 310, carry pinions 435 adapted to engage with and disengage from the racks by suitable mechanism well-known in the Wales machine and not herein shown.

Depressing numeral keys 117 in the various denominations, to represent an amount 20 to be accumulated on the counters 490, projects the corresponding stops 115 into the paths of the positioning racks 310, and displaces the detents 221 corresponding to the denominations wherein keys have been depressed, and overlying their respective files of stops. The detents 221 are each journaled on a cross rod 202 and springs 280 restore the 25 detents to effective position.

Turning the main drive shaft forwardly 30 raises the arm 210 and causes the wiper 256 to traverse the cam slot 220^m in the crank 220, to rock the shaft 265 and withdraw the restraining and restoring bar 205 relatively to the front supporting arms 312. The springs 383 are thus free to advance 35 the positioning bars 310 until the latter are arrested by the projected stops 115 or by the detents 221 in denominations wherein no keys have been depressed. The counters 490 remain out of engagement with the positioning racks 310 until near the end of the forward stroke of the main drive shaft and after the racks have completed their advance, whereupon the counters drop to mesh their pinions 435 with the racks (see 45 Fig. 2).

Releasing the main drive shaft at the end of its forward stroke enables a main restoring spring 285 to return the shaft and its 50 connected parts to their home positions, during which return stroke, the restraining and restoring bar 205 presses against the front arms 312 to retire the advanced positioning racks and thereby turn the counters engaged therewith, to accumulate thereon the amount represented by the depressed keys.

Near the end of such return stroke, but after the racks have been fully retired, the 55 counters and their pinions are disengaged from their racks, and the keys 117 restored to normal position.

The rearward extensions 311^m of the rear supporting arms 311 are connected by links 60 315 to the rearward typebars 514, whose

heads each carry a row of types 561 corresponding to the designations of the respective keys 117 in the related denominations. The drive springs 383, as they advance their drive members or positioning bars 310, rock 70 the rearward extensions 311^m to lift the typecarriers 514 and successively present the types 561 to the printing line. The stops 115 arrest the drive members 310 and typecarriers 514 to position the types at the 75 printing line corresponding to the depressed keys, and the detents 221 arrest the positioning bars and typecarriers when the cipher types are at the printing line.

A recocking bail 509^a (Fig. 1) normally 80 holds a series of denominationally arranged printing hammers 510, journaled on a shaft 500, in cocked position against the tensions of driving springs 580. In addition, a universal catch 518 takes over the series of 85 hammers, each of which latter is also provided with a suitably journaled individual latch 511 engaged with their respective hammers by springs 581.

Displacement of the individual latches 90 511 is effected by means of trip bars 513, controlled by the extensions 311^m. The extensions 311^m normally hold the trip bars 513 in idle position against the tension of their springs 583. As the rearward extensions 95 311^m swing upwardly on the forward stroke of the main drive shaft, to locate the types at the printing line, they release the trip bars 513 to the action of their springs 583 which lift and press the bars against 100 the corresponding individual latches 511 to displace the latter relatively to their hammers 510.

Normally, the uppermost or cipher type 105 561 of each typecarrier 514 lies just below the printing line, but the positioning bars 310 have sufficient throw on the forward stroke, before their arrest by their detents 221, to lift the typecarriers and position the cipher types at the printing line, though 110 the limited travel thus permitted the rearward extensions 311^m is not sufficient to enable the trip bars 513 to displace the corresponding hammer latches 511. To effect the imprint of ciphers to the right of a significant digit, the hammer latches 511 each carry a tail 518^a adapted to extend beneath the adjacent hammer latch to the left so that when the last-named latch is tripped, it will strike the tail of the hammer latch immediately to the right to trip such latch in case no keys have been depressed in the 115 denomination corresponding with such right hand hammer latch.

The recocking bail 509^a is also withdrawn 120 during the forward stroke, by means well-known in the Wales machine, so that the universal catch 518 alone retains in cocked position, those hammers whose latches 511 have been displaced.

After the proper types have been positioned, the universal catch 518 is raised by suitable means (not shown) to release the hammers 510 which, under the influence of their drive springs 580, strike plungers 562^b and drive the latter against the positioned types to effect an impression on the paper carried by the platen 2094.

The latches 511 to the left of the digit of highest value set up on the keyboard, remain effective to prevent imprints from the cipher types of their corresponding typecarriers.

Retirement of the positioning racks 310, during the return stroke of the main drive shaft, lowers the rearward extensions 311^a which, in turn, retract the trip bars 513 to idle position, to enable the individual hammer latches to become effective, and also lowers the typecarriers 514.

The recocking bail 509^a restores the hammers to set position and the universal catch 518 snaps over them.

In machines adapted for statement and other lines of work, it is customary to pivotally secure one or more of the tails 518^a to their latches, as at 554^a, and arrange a controllable slotted slide 515^c, through the slot in which the pivoted tail extends, to shift the tail to its effective and ineffective positions, depending upon whether or not it is desired to print characters in a single column or in two separate columns simultaneously.

Such so-called split mechanism is shown more clearly in U. S. patent to Wilgus 1,260,615, March 26, 1918, to which reference is made for a more complete explanation thereof.

When the machine is equipped for statement work, it is customary to form the split between the sixth and seventh rows or denominations of a machine having nine denominational rows of keys, and to equip the keys 117 and the typecarrier of the ninth row or denomination with month designations, as shown in Fig. 3, the day of the month being set up on the numeral keys of the seventh and eighth denominational rows, when the tail 518^a is shifted to idle position to form the split.

The three extra keys 117^a (Fig. 3) to complete the twelve month designations may be located alongside and to the left of the keys of the ninth denomination, and control stops 115^a located closely adjacent the file of stops 115 of the same denomination to control the advance of the corresponding positioning bar 310 and position the proper designating types at the printing line, it being customary to mount all twelve of the month designating types in the typecarrier appropriated to the ninth bank. Preferably, a special detent 221^b coacts with the month stops 115, 115^a.

Furthermore, since digits from "1" to "3" only are required in the typecarrier of the eighth denomination to indicate the day of the month, it is customary to substitute commercial abbreviations, such as BL; DR; 70 CR; etc., in place of the remaining six digits in such denominational typecarrier, although for the sake of increasing the capacity of the machine when used as a normal machine, without the split, I have 75 shown but three such abbreviations. The keys 117^a appropriated to these characters, are similarly designated.

A machine thus equipped, and with the split formed between the sixth and seventh 80 rows of keys, is adapted to perform work, as follows:

Dr	100.00	
Jan 31	47.50	
Feb 3	21.99	85

Owing to the formation of the split in the printing section, tripping of the individual hammer latch 511 to the right of the seventh row to effect cipher printing, is 90 interrupted, and if no keys are depressed in the right hand rows immediately adjacent the seventh row, a blank space is left between the month designation and the amount, as indicated in the foregoing example. With the shiftable latch tail 518^a in effective position, as when the machine is used as a normal machine, displacement of the hammer latch 511 of the seventh row, will in turn, effect the displacement of the 100 hammer latch to the right thereof, and so on.

It is also obvious that the continued tripping operation of the hammer latches to the left of the split is uninterrupted from the ninth to and including the seventh row or 105 denomination.

In view thereof, depression of any of the keys controlling the printing of the commercial abbreviations which, in the present instance, take the places of the seventh, 110 eighth and ninth numeral keys in the eighth denomination, followed by an operation of the main drive shaft, would ordinarily effect the tripping of the hammer latch in the seventh bank and the consequent imprint of a cipher immediately adjacent the abbreviation. Thus, in the example above given, the first amount would be erroneously printed as—

Dr 0	100.00	120

The invention disclosed in Pentecost 1,282,282, October 22, 1918, is designed to prevent the imprint of such irrelevant cipher immediately to the right of the abbreviation or character, other than a numeral, and the present invention is directed to mechanism to accomplish the same result and constitutes an improvement upon the earlier form of mechanism. 130

In that embodiment of the invention disclosed in the above patent, the typecarrier, as it ascends to position the lower commercial abbreviation types at the printing line, 5 brings a wiper into contact with a cam member connected to a normally idle locking member to shift the latter to effective position relatively to the printing hammer of that denomination wherein it is desired to 10 eliminate printing, so that although the corresponding hammer latch is tripped, the hammer is held against operation.

There are a considerable number of parts required in the manufacture of the patented 15 embodiment, and a very nice adjustment is necessary for its proper operation.

My invention materially reduces the number of parts, and requires but little adjustment, and I have contrived to attain the 20 same result in a much simpler manner than heretofore.

Thus, I provide the detent 221 appropriate to that denomination wherein the printing is to be eliminated, with a lateral 25 lip 221^m extending into the path or paths of one or more of the stops 115 which control the positioning of the type characters in connection with which the printing of ciphers is not desired.

30 In the present instance, the detent 221 appropriated to the seventh row or denomination carries a lip or projection 221^m extending over and into the paths of the three stops 115 actuated by the three keys 117^m (Fig. 3) of the eighth row or denomination, 35 which stops respectively operate to arrest the corresponding positioning bar 310 and the typecarrier 514 to locate the types "BL," "CR" and "DR" at the printing line.

40 Obviously, depression of any of these three keys in the eighth denomination will not only set the appropriate stop 115^m (Figs. 3 and 4) and lift the correlated detent 221, but will also, by contact with the 45 lip 221^m, displace the detent 221 to which the lip is connected, which last-named detent is associated with the denomination wherein it is desired to eliminate printing.

Also, it is plain that the last-named detent 50 may be displaced by a larger or smaller number of stops in another denomination, depending upon the width of the lip 221^m.

Assuming the depression of one of the character keys 115^m, the drive shaft, on its 55 forward stroke, withdraws the restraining and restoring bar 205 and frees the entire series of positioning bars 310 to the action of their springs 383, which advance the bars until the latter are arrested by the stops 115 60 and 115^m projected into their paths or by the effective detents 221 in denominations wherein no keys have been depressed. But depression of any of the keys 115^m displaces the detent in another denomination, and 65 hence the positioning bar 310 corresponding

therewith is free to advance to its extreme forward limit because no stops have been projected in such denomination.

As shown in Fig. 2, the positioning bar 310, in advancing to its extreme forward 70 limit, passes over and past the stop 115 which, when projected, arrests the positioning bar when the lowermost type "9" is at the printing line, the excess throw of the positioning bar operating to lift the typecarrier 514 connected thereto to locate the lowermost type "9" above the printing line and out of the path of its denominational plunger 562^b, so that although the corresponding denominational hammer latch 511 80 has been tripped by its bar 513, and the hammer 510 fires, its action is ineffective to print a character because no character is located at the printing line.

To prevent the dislocation relatively to 85 its support, of the firing pin 562^b corresponding with that denomination, printing in which it is desired to avoid, I prefer to stationarily mount a dummy type 564^f in the corresponding typecarrier 514, beneath 90 the lowermost type 561, as shown in Figs. 1 and 2. As the typecarrier reaches its highest position, due to the excess travel permitted the positioning bar by the displaced rack detent, it locates the dummy 95 type opposite its plunger 562^b so that the latter, when driven by the hammer, will strike and be arrested by the dummy type.

The extent of withdrawal of the restraining and restoring bar is sufficient to permit 100 the positioning bar to complete such excessive advance, and in practice, the forward end of this positioning bar may be slightly shortened or cut off to prevent its arrest by the familiar bail 204, and the front supporting arm may be recessed, as at 312^m, to insure the completion of the excessive stroke. To compensate for such shortening of the 105 positioning bar so that, under ordinary circumstances, its detent 221 will arrest it, to 110 position the uppermost or cipher type at the printing line, I make the corresponding detent 221 slightly longer to extend farther rearwardly.

Furthermore, in order to afford sufficient 115 clearance for the extreme ascent of the corresponding rearward extension 311^m, I may cut away the familiar universal extension-arresting bar 529^b, as at 529^m.

These changes, however, are merely structural, it being plain that other changes may be adopted to provide the necessary clearances, without deviating from my invention.

While the herein illustrated embodiment 125 of my invention, discloses a mechanism wherein the drive member is permitted an excess travel to position the regular printing types of the typecarrier above the printing line, and locate a dummy at the print- 130

ing line, to render the impact of the hammer ineffective, the dummy is employed merely to arrest the plunger or firing pin against accidental disengagement with its support, and may be dispensed with in instances where the hammers directly impinge against the types. In such instances, the hammer would merely contact the front edge of the typecarrier at the extreme end 10 of its throw.

The drive member 310 during its retirement, after such excessive advance, will turn its corresponding counter 490 a complete revolution or semi-revolution, as the 15 case may be, depending upon whether or not the counters carry one or two series of numerals arranged in tandem, and this rotation will trip the usual carrying mechanism to add "1" to the counter of next 20 higher denomination, but since the registration on the counters to the left of the split is disregarded in any event, when printing month designations, such rotation is of no consequence.

25 Other changes and alterations may be made in the form and arrangement of the parts set forth, without departing from the spirit and scope of my invention.

What I claim as new, is:—

30 1. In a calculating machine, the combination with a plurality of denominational trains of accumulating and printing mechanism, each train including a file of manually-settable stops; a typecarrier provided 35 with a series of types; a hammer to impress the types on the paper; a drive member for the typecarrier; the drive member adapted to coact with the stops; and a detent to arrest the drive member in case no stops are 40 set in the path thereof; the detent adapted to be displaced by any of the stops in its corresponding denomination; of means to enable a stop in one denomination to control the drive member in another denomination, 45 whereby to prevent type impressions in the last-named denomination.

2. In a calculating and listing machine, the combination with denominational trains of mechanism, each train including a drive 50 member; a file of stops shiftable into and out of effective position, to variously arrest the drive member; a detent displaceable by the stops, to arrest the drive member when no stops are shifted to effective position; a 55 typecarrier and types controlled by the drive member, to position that type at the printing line which corresponds with the particular effective stop; and a printing hammer to impress the positioned type; of 60 means to enable a stop in one denominational train to control the excursions of the drive member in another denominational train; and a dummy mounted in the typecarrier associated with such last-named 65 drive member, and positioned at the print-

ing line when the excursions of the typecarrier and its drive member are controlled by the stop in another denominational train, to arrest the printing hammer.

3. In a calculating and listing machine, 70 the combination with denominational trains of mechanism, each train including a drive member; a file of stops shiftable into and out of effective position, to variously arrest the drive members; a detent displaceable by 75 the stops, to arrest the drive member when no stops are shifted to effective position; a typecarrier and types controlled by the drive member, to position that type at the printing line which corresponds with the 80 particular effective stop; and a printing hammer to impress the positioned type; of means operated by a stop in one denominational train, to control the excursions of a drive member in another denominational 85 train whereby the typecarrier associated with the drive member so controlled; positions no type at the printing line.

4. In a calculating machine, the combination with a plurality of denominational 90 trains of accumulating and printing mechanisms, each train including a file of manually-settable stops; a typecarrier provided 95 with a series of types; a drive member for the typecarrier; the drive member adapted to coact with the stops to position the typecarrier with the proper type at the printing line; a printing hammer; and a detent to arrest the drive member in case no stops are set in the path thereof; the detent 100 adapted to be displaced by any of the stops in its corresponding denomination; of means to enable a stop in one denomination to control the drive member in another denomination, whereby the latter is permitted 105 an excessive travel to shift its typecarrier to a position wherein no type are located at the printing line.

5. In a calculating machine, the combination with a plurality of denominational 110 trains of accumulating and printing mechanisms, each train including a file of stops shiftable to and from effective position; a typecarrier having a series of types; means to impress the types when located at the 115 printing line; a drive member for the typecarrier, whose excursions are variously arrested by the stops; and a detent to arrest the drive member in case no stops are shifted in the path thereof; the detent adapted to be 120 displaced by any of the stops in its corresponding denomination; of means to enable a stop of one denomination to control the drive member of another denomination, including a projection from the detent appropriate to the denomination whose drive member is to be controlled, which projection lies in the path of at least one of the stops in another denomination, and a 125 dummy type mounted in the typecarrier actu- 130

ated by the controlled drive member, to be positioned at the printing line, during an operation of the machine in which the controlling stop is set.

5 6. In a calculating machine, the combination with a plurality of denominational trains of accumulating and printing mechanism, each train including a row of keys; 35 a file of settable stops controlled thereby; a drive member, the extent of whose excursions is regulated by the stops; a detent dis-
10 placeable by any of the stops in its file, to arrest the drive member when the stops are 40 inactive; a typecarrier positioned by the drive member relatively to the printing line, and bearing a row of types corresponding to the designations on the consonant row of keys; a printing hammer to impress the type 45 positioned at the printing line; a latch to retain the printing hammer inoperative; means to trip the adjacent latch associated with the denominational train of accumulating and printing mechanism to the right; 50 and a dummy type on one of the typecarriers in addition to the printing types; of means controlled by one or more stops in one denominational train to displace the de-
15 tent associated with the drive member of 55 another denominational train, whereby to permit the maximum advance of the drive member and the consequent positioning of its typecarrier relatively to the printing line to bring the dummy type opposite the print- 60 hammer, and thus render the printing action of the hammer ineffective.

20 25 30 35 40 45 50 55 60

7. In a calculating machine, the combina-

tion with a plurality of denominational trains of accumulating and printing mech-
10 anism, each train including a row of keys; 35 a file of settable stops controlled thereby; a drive member, the extent of whose excursions is regulated by the stops; a detent dis-
15 placeable by any of the stops in its file, to arrest the drive member when the stops are 40 inactive; a typecarrier positioned by the drive member relatively to the printing line, and bearing a row of types corresponding to the designations on the consonant row of keys; a printing hammer to impress the type 45 positioned at the printing line; a latch to retain the printing hammer inoperative; means to trip the adjacent latch associated with the denominational train of accumulating and printing mechanism to the right; 50 and a dummy type on one of the typecarriers in addition to the printing types; of means controlled by one or more stops in one denominational train to displace the de-
20 tent associated with the drive member of 55 another denominational train, whereby to permit the maximum advance of the drive member and the consequent positioning of its typecarrier relatively to the printing line to bring the dummy type opposite the print- 60 hammer, and thus render the printing action of the hammer ineffective.

FRANK B. PALMER.
